UNITED STATES PATENT OFFICE.

MAX JACOBS, OF BOSTON, MASSACHUSETTS.

GARMENT-LENGTH GAUGE.

Application filed May 21, 1923. Serial No. 640,624.

To all whom it may concern:

Be it known that I, MAX JACOBS, a citizen of the United States, and a resident of the city of Boston, in the county of Suffolk and 5 State of Massachusetts, have invented a new and Improved Garment-Length Gauge, of which the following is a full, clear, and exact description.

This invention has relation to gauges and 10 has particular reference to a device for gaging the length of a garment and for facilitating the forming of a hem therein.

Heretofore it has been the common practice, especially in determining the place for 15 turning or forming a hem at the lower edge of a garment, to first place the garment on a form, employ a tape measure to measure from the neck to the lower edge and make a mark, then by use of a yardstick measure 20 from the floor to the first mark and using this measure on the yardstick repeating the markings around the garment to indicate the place at which the hem is to be turned. This practice consumes an undue length of 25 time and often the markings are not readily erased from certain fabrics or cloths. Furthermore if the form is accidentally raised or lowered there is a chance for a mistake to be made which will affect the 30 proper hanging of the finished garment.

It is, therefore, an object of the present invention to overcome the above recited disadvantages and objections to the present practice by providing a garment length 35 gauge which is directly attached to the form whereby the turning of a hem of a garment when arranged on the form may be readily gaged, pinned and the hem removed in substantially a continuous operation, thus 40 eliminating the necessity of marking the place of turning or the use of tape measures and yardsticks.

As a further object the invention contemplates a gauge which is adjustable on the 45 form or garment support and is itself adjustable for special lengths of garments and furthermore a gauge which is not affected either by the accidental or intentional raising or lowering of the garment 50 form or support.

As a still further object the invention contemplates a gauge which is extremely simple in its construction and mode of use, inexpensive to manufacture and produce, 55 highly efficient in its purpose and capable of folding when not in use whereby the

same may occupy a minimum space for storage or shipment.

With the above recited and other objects in view, the invention resides in the novel 60 construction set forth in the following specification, particularly pointed out in the appended claims and illustrated in the accompanying drawings, it being understood that the right is reserved to embodiments other 65 than those actually illustrated herein to the full extent indicated by the general meaning of the terms in which the claims are expressed.

In the drawings:—

Figure 1 is a perspective view of a garment length gauge constructed in accordance with the invention and illustrating its application to a garment supporting device.

Fig. 2 is an enlarged detail front view of 75 the gauge.

Fig. 3 is a vertical sectional view therethrough illustrating the position of the same for facilitating the removal of the hem.

Fig. 4 is a transverse sectional view taken 80 approximately on the line 4—4 of Fig. 2.

Fig. 5 is a similar view taken approximately on the line 5—5 of Fig. 2.

Referring to the drawings by characters of reference, A designates a dress form or 85 garment supporting device which is supported by a standard B from a suitable base C. The dress form or garment supporting device is provided with a depending skirt of wire framework D.

The garment length gauge which constitutes the invention consists of an attaching section 10 which is longitudinally slotted as at 11 to receive therethrough a threaded shank 12 having an engaging head 13 at 95 one end which coacts with one of the wires of the framework D. A thumb nut 14 is threadedly engaged with the free end of the shank 12 which projects through the slot 11 whereby the attaching section 10 is rigidly secured to the framework D and is vertically adjustable thereon by manipulation of the fastening means. A second section 15, the lower edge 16 of which constitutes the gaging edge, is suitably connected with the attaching section 10 whereby the gaging edge normally projects below the framework D in order that the lower end of the garment may be turned inwardly and upwardly thereunder to form a hem and whereby the lower edge may be moved to a position to facilitate the removal of 110

the hem therefrom. In the present instance the upper edge of the section 15 is provided with transversely spaced knuckles 16 and the lower edge of the attaching section 10 5 with similarly formed staggered knuckles 17 through which a hinge pin 18 extends whereby the section 15 may be swung with respect to the section 10.

In use and operation, the garment is supported from the form or supporting device A upon which a plurality of length gauges are arranged. The operator turns up the lower edge of the garment to embrace the lower gaging edge 16 of the section 15 and temporarily pins the hem in place, after which the section 15 is swung upwardly to allow for a sufficient slack in the garment to permit of the removal of the pinned hem from the gauge. In order to provide means for gaging a hem in a garment of a special length an adjustable leaf 19 is provided, the lower edge 20 of which forms a gaging edge which is projectable below the regular gaging edge 25 16 of the section 15. The means for adjustably associating the leaf 19 with the section 15 consists of a slot 21 formed in the leaf 15 and a clamping bolt 22 which passes through the slot and through an 30 opening in the leaf 19 and a thumb nut 23 threadedly engaged with the bolt for securing the leaf in its adjusted positions. Preferably the leaf 19 is provided with suitable graduations 24 on its face to indicate the distance the gaging edge 20 is projected beyond the gaging edge 16.

From the foregoing it will be seen that an extremely simple and inexpensive garment length gauge is provided which is 40 adapted for detachable association with a garment support whereby the operation of gaging the length of a garment and forming of a hem therein is greatly facilitated.

I claim:

45 1. A garment length gauge adapted for attachment to a garment supporting device, said gauge having a member presenting a

lower gaging edge around which the lower edge of the garment is adapted to be turned up for forming a hem, and means for permitting the movement of said member to produce a sufficient slack in the garment to allow for the removal of said turned up part from the gaging edge. 50

2. The combination with a garment supporting device, of a garment length gauge comprising a member having a lower gaging edge around which the lower edge of a garment on the supporting device is adapted to be turned up for forming a hem, 60 said member being movable to a position to allow for the removal of the turned up part from the lower gaging edge thereof. 65

3. A garment length gauge adapted for attachment to a garment supporting device, 70 said gauge including a member having its lower edge normally disposed in a position to allow for the turning up of the lower edge of a garment on the supporting device thereunder to form a hem, and means whereby the said member is movable to a position to produce a slack in the garment whereby to allow for the withdrawal of the turned up part thus formed from 75 said edge. 80

4. A garment length gauge adapted for attachment to a garment supporting device, said gauge comprising a pair of sections, a detachable and adjustable connection between the upper section of the gauge and the supporting device and a connection between the lower section and the upper section, whereby in the normal arrangement of the sections the lower edge of the lower section may be utilized for the turning of the lower end of a garment supported by the supporting device therearound to form a hem and to further permit of relative movement between the lower section and the upper section to produce 90 a slack in the garment for effecting the removal of the turned lower end thus formed, from the lower edge of the lower section. 95

MAX JACOBS.
